T. J. THATCHER.
AIR PIPE COUPLING.
APPLICATION FILED APR. 9, 1903.

NO MODEL.

UNITED STATES PATENT OFFICE.

THOMAS J. THATCHER, OF COLUMBUS, OHIO, ASSIGNOR OF ONE-THIRD TO
C. D. SAVIERS, OF COLUMBUS, OHIO.

AIR-PIPE COUPLING.

SPECIFICATION forming part of Letters Patent No. 735,316, dated August 4, 1903.

Application filed April 9, 1903. Serial No. 151,772. (No model.)

To all whom it may concern:

Be it known that I, THOMAS J. THATCHER, a citizen of the United States, residing at Columbus, in the county of Franklin and State of Ohio, have invented a certain new and useful Improvement in Air-Pipe Couplings, of which the following is a specification.

This invention relates to the train-pipes of air-brake systems for railway-cars, and has to its object to provide an improved coupler and manner of rigging the train-pipes, so as to automatically accommodate the same to the movements of the cars in rounding curves, under draft and buffing strains, and in passing over rail-joints and other uneven portions of the track without danger of breaking or impairing the coupling in any manner whatsoever.

With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a perspective view of a train-pipe coupler embodying the features of the present invention. Fig. 2 is a vertical longitudinal sectional view thereof. Fig. 3 is a detail sectional view on the line 3 3 of Fig. 2, and Fig. 4 is a detail cross-sectional view on the line 4 4 of Fig. 2.

Like characters of reference designate corresponding parts in each and every figure of the drawings.

Although the device of the present invention has not been shown in connection with a car, it will be understood that it is hung from the bottom of the car, preferably by means of a substantially U-shaped hanger 1, the opposite upper end portions of which are provided with outturned flanges 2, having perforations for the reception of suitable fastenings to secure the flanges flat against the center sills or draft-timbers of the bottom frame of a car, with the lower portion of the hanger disposed below the draft-timbers, so

as to support the train-pipe coupler below the car-coupler. This disposition of parts being so apparent it has not been deemed necessary to illustrate anything except the 55 coupler and the hanger therefor.

Within each hanger there is a vertically-slidable member 3, preferably in the form of a rectangular block, which is provided in its opposite vertical edges with open-ended 60 grooves 4, forming guideways for the reception of the respective upright portions of the hanger, whereby the block is held against horizontal movements and is capable of sliding vertical upon the hanger, the cross-bar 65 5 at the bottom of the hanger forming a stop or support to prevent the block from falling downwardly from the hanger. Normally the block of course rests upon the bottom of the hanger, and therefore has a vertical play according to the length of the hanger.

In front of the hanger is the coupler proper, embodying a relatively fixed head 6, from which extends a reduced rearwardly-directed and polygonal neck portion 7 integral therewith and working endwise through a corresponding central polygonal opening 8 in the guide block or member 3, whereby the coupler may move back and forth in the longitudinal direction of the train and may also move 70 vertically with the guide-block 3, but is held against lateral bodily movement. Throughout the neck and head extends a longitudinal bore or passage 9, and a metallic pipe 10 is screw-threaded into the rear end of this passage or otherwise rigidly connected to the rear end of the neck in communication with the passage 9 to form a continuation thereof and also to form a guiding-stem. For the support of the rear end of the pipe or stem 75 10 there is a yoke-shaped frame 11, the rear end of which is provided with an opening for the slidable reception of the tubular stem, while the front end portions of the sides of the frame pierce the rear flanges of the guide-block 3 and extend across the backs of the guideways 4, suitable fastenings 12 being set through the sides of the frame and into the block to rigidly secure the frame thereto. It will of course be understood that the sides 80 90 of the frame are let in flush with the backs of the guideways 4, so as not to interfere

with the free slidable movement of the block. A helical spring 13 embraces the tubular guide-stem 10 and bears in opposite directions against the relatively fixed rear end of the frame and against the shoulder formed by the rear end of the neck 7, whereby the coupler is yieldably held at its forward limit and may give or yield rearwardly against the tension of the spring under buffing strains. 5 To limit the forward movement of the coupler, an annular stop-shoulder, flange, or collar 14 is rigidly secured to the rear end of the tubular stem 10 and in rear of the frame 11, so as to normally lie against the rear end 15 of the frame and hold the coupler from being displaced under the action of the spring. The tubular stem 10 is projected rearwardly beyond the shoulder or flange 14 and is provided with an external coarse screw-threaded portion 15 for engagement by a flexible hose-section 16, which is in turn connected to the adjacent train-pipe in any preferred or common and well-known manner, said flexible hose-section being designed to accommodate 20 for the endwise play of the coupler.

As best shown in Fig. 3 of the drawings, it will be seen that the front end of the coupler-head 6 is provided with an arcuate recess, seat, or reentrant portion 17, within which is 25 loosely fitted the correspondingly-convexed rear end of a movable or oscillatory head member 18, the two members being connected by means of top and bottom plates 19 and 20, each of which is rigidly connected to the fixed head member 6 by means of suitable fastenings 21, and the movable member being pivotally connected to the plates by the upper and lower vertically-aligned pivots 22. By this manner of connection it will be seen that the movable 30 head member 18 may swing horizontally or oscillate upon the relatively fixed member 6, so as to prevent disengagement of a pair of couplers when the cars are rounding a curve. The front end of each plate 19 and 20 is inclined rearwardly from the middle thereof in line with the pivot 22 to form shoulders 23, and correspondingly-inclined shoulders 24 are formed upon the top and bottom of the movable head member, whereby the shoulders 25 are adapted to strike the corresponding shoulders 23, and thereby limit the lateral swing of the movable head member.

In the front end of the movable head member 18 a longitudinal recess is formed to provide a socket or pocket 25, which is located at one side of the longitudinal center of the member, and the opposite side of the member is reduced to form a tongue or projection 26, shaped to have a working fit within the 30 socket of a coöperating coupler. Throughout the length of the movable head member there is a longitudinal passage 27, which is disposed at one side of the pivot 22 with its rear end portion bowed inwardly to pierce 35 the back of the member at the longitudinal center thereof, while the forward portion of the passage, which enters the tongue 26, has

a terminal lateral bend 28, which pierces the inner side of the tongue, there being a suitable packing-ring or washer 29 let into the inner face of the tongue and embracing the forward terminal of the passage. When two couplers are in coupled engagement, as indicated in Fig. 3 of the drawings, it will be seen that the front bowed terminals 28 of the 75 passages 27 are in mutual alinement or registered, so as to form a continuous or uninterrupted passage from one coupler to the other, the rubber or other suitable yieldable washers or packing-rings 29 insuring an air-tight joint between the two passages. 80 To insure a continuous uninterrupted communication between the passages 9 in the fixed member 6 and the rear end of the passage 27 in the oscillatory member 18, externally-screw-threaded short pipe-sections or nipples 30 and 31, respectively, are fitted to said passages, the rear end of the movable member 18 being provided with a recess 32 to afford an interspace between the two nipples, the latter being connected by a flexible tube 33, thereby providing a flexible joint or coupling between the two passages 9 and 27. By this construction the movable member 18 may swing laterally without interrupting the 95 communication between the passages 9 and 27. It will here be stated that the arcs of the convexed rear end of the movable member 18 and the recess 17 in the fixed member 6 are struck from the pivot 22 as a center in 100 order that there may be no binding of the fixed and movable members.

From the foregoing description it is apparent that each coupler is hung intermediately from the bottom of a car in a guide 105 which is fixed against horizontal movements and is capable of vertical movements, and when two cars are brought together the projections of the couplers thereof enter the sockets of the relatively opposite couplers, 110 and thereby automatically effect a coupling of the air-pipes, the couplers of course yielding longitudinally under the buffing strain, and thereby preventing damage to the couplers and rigging therefor by the force of the 115 impact.

As hereinbefore set forth, the train-pipe couplers are hung below the car-couplers to be out of the way thereof and are also entirely independent of the couplers, and therefore may be applied to any type of car without regard to the character of car-coupler employed. Furthermore, opposite train-pipe couplers are free to be separated longitudinally without removing any fastening devices whatsoever, whereby the couplers freely and automatically separate when the cars are uncoupled, and should the car-coupling break the train-pipe couplers will separate without damage thereto or to any part of the 120 rigging therefor.

Having thus described the invention, what is claimed, and desired to be secured by Letters Patent, is—

1. A train-pipe coupler, embodying a relatively fixed member having an air-passage therethrough, a movable member pivotally connected to the fixed member and provided with an air-passage, and a flexible tubular connection between the two passages to permit swinging movement of the movable member without interrupting the communication between the two air-passages. 5
2. A train-pipe coupler, embodying a relatively fixed member having an air-passage therethrough, and provided in its front end with a seat or recess, a movable member having an air-passage therethrough and pivoted within the seat of the fixed member, the rear end of the movable member being cut away across the rear end of the air-passage thereof, and a flexible tubular coupling connecting the air-passages and lying in the cut-away portion of the movable member. 15
3. A train-pipe coupler, embodying a relatively fixed member having an air-passage formed therethrough and provided in its front end with a segmental seat, a movable member having an air-passage formed therethrough with its rear convexed end pivoted within the seat and having a working fit against the concaved back of the seat, said convexed rear end also having a recess intersecting the air-passage of the member, and a tubular flexible coupling connecting the adjacent ends of the air-passages and lying in the recess of the movable member. 25
4. A train-pipe coupler, embodying a relatively fixed member having an air-passage formed therethrough and provided in its forward end with a seat, a movable member pivoted within the seat and provided in its front end and at one side of its longitudinal center with a socket and at its opposite side with a tongue shaped to correspond with the socket, there also being an air-passage extending through the back of the movable member and into the tongue with its forward end directed laterally inward into communication with the socket, the back of the movable member being provided with a recess intersecting the rear end of the air-passage, and a tubular flexible coupling connecting the air-passages of the members and lying in the recess in the back of the movable member. 35
5. A train-pipe coupler comprising a relatively fixed member having a seat in its forward end and provided with an air-passage communicating with the seat, plates secured to opposite sides of the member and projected at the front thereof, a movable member having its rear end located within the seat of the fixed member and pivoted to the projected portions of the plates, the reduced portion of the movable member forming stop-shoulders for engagement with the plates to limit the pivotal movement of the member, said movable member also having an air-passage formed therethrough, and a tubular flexible coupling between the air-passages of the two members. 55
6. In a coupler, the combination with a hanger, of an abutment carried thereby, a coupler having a stem working through the abutment, a guide-frame carried by the abutment and slidably receiving the rear end of the stem, and a spring bearing at its front end against the stem and at its rear end against the guide-frame. 60
7. In a coupler, the combination with a hanger, of a vertically-movable abutment carried thereby, a coupler having a stem working through the abutment, a frame carried by and movable with the abutment and slidably supporting the rear end of the stem, and a spring bearing at its front end against the stem and at its rear end against the frame. 75
8. In a coupler, the combination with a hanger, of a vertically-movable abutment carried by the hanger, a coupler having a polygonal stem working through a correspondingly-shaped opening in the abutment and provided with an air-passage, a tubular stem member connected to the rear end of the air-passage and rigidly carried by the polygonal stem portion, a yoke-shaped guide-frame carried by the abutment and slidably receiving the rear end of the tubular stem member, and a helical spring embracing said tubular stem member with its front end bearing against the polygonal stem portion of the coupler and its rear end bearing against the guide-frame. 80
